UNITED STATES PATENT OFFICE.

ALEXANDER D. DU BOIS, OF CHICAGO, ILLINOIS, ASSIGNOR TO WESTERN ELECTRIC COMPANY, OF CHICAGO, ILLINOIS, A CORPORATION OF ILLINOIS.

MULTIVOLTAGE-SPEED CONTROLLER.

No. 836,019.

Specification of Letters Patent.

Patented Nov. 13, 1906.

Application filed January 13, 1906. Serial No. 295,839.

To all whom it may concern:

Be it known that I, ALEXANDER D. DU BOIS, a citizen of the United States, residing at Chicago, in the county of Cook and State of Illinois, have invented a certain new and useful Improvement in Multivoltage-Speed Controllers, of which the following is a full, clear, concise, and exact description.

My invention relates to speed-control systems for electric motors wherein both variations in the field strength and in the armature-current are utilized to vary the speed of the motor.

The invention has for its object to provide an arrangement of circuits and apparatus whereby a motor may be employed in connection with circuits of varying voltage and given a wide range of speed.

My invention also contemplates a construction permitting the field-resistance controller, which is at all times independent of the armature-resistance controller, to be set for any desired speed with the armature on any desired voltage and the motor stopped and started by operating the armature-resistance controller without disturbing the adjustment of the field-controller.

In accordance with my invention I provide a switch-arm controlling the connection of high and low voltage circuits with the motor-armature, the switch-arm being adapted to be operated by mechanism controlled by the field-resistance-controlling arm in its movement, said mechanism when operated shifting the switch-arm from one circuit to another. The field-resistance arm is adapted when it reaches a given point in its travel—as, for example, as it passes from the last contact of the resistance to the first—to operate said mechanism and shift the switch-arm, for example, from the low-voltage to the high-voltage circuit. The field-resistance controller may then be moved to bring the entire resistance into the field-circuit, so that the motor is brought to full speed with a weakened field and the maximum of current in its armature.

A further feature of my invention consists in placing the field resistance under the control of the armature-starting arm, the field-resistance controller being, however, at all times independent of the starting-arm. With this arrangement the field-resistance controller may be set for any desired speed with

the motor-armature in the high or low voltage circuit, as desired, and the motor started, brought up to the desired speed, or stopped by simply operating the starting-arm without disturbing the adjustment of the field-resistance controller. The starting-arm controls the interpolation of the predetermined field resistance into the field-circuit, preferably by means of shunts about succeeding sections of the field resistance, which are opened by the starting-arm in its movement to gradually cut the predetermined field resistance into the field-circuit.

I will describe my invention by reference to the accompanying drawings, in which—

Figure 1 is a diagram illustrating the preferred embodiment thereof; and Figs. 2, 3, and 4 are detail views of the switch controlling the connection of the armature with the high and low voltage circuits, showing the switch in its alternative positions.

The same characters of reference designate the same parts throughout the several figures of the drawings.

I have shown my invention applied to a system of two voltages or the well-known three-wire system.

The armature *a* of the motor is included in the main conductor 1 between the line and the controlling-arm *b'* of the armature-starting resistance *b*. The arm *b'* is arranged to sweep over contacts of the usual resistance until it reaches the plate *b*², when the resistance is all cut out of the armature-circuit. The plate *b*² is connected by a conductor 4 with the contact *c'* of a knife-switch *c*. The mate contact *c*² of said switch is connected with conductor 2, the neutral wire of the system, and the switch-arm *c*³ normally connects said contacts *c'* *c*² together, so that when the starting-arm engages its contacts 1-2-4. The switch-arm *c*³ when moved out of engagement with its contacts *c'* *c*² is adapted to engage contacts *c*⁴ *c*⁵ and as it continues its movement is brought into engagement with contact *c*⁶, connecting the three contacts together. Contact *c*⁶ is connected by conductor 5 with contact *c'* on the other side of the switch-arm and by conductor 6, including a resistance *R* with contact *c*⁵. The contact *c*⁴ is connected with the main conductor 3 leading to the line. When the switch-arm *c*³ is thrown into engagement

with the contacts $c^4 c^5$, the armature is in the high-voltage circuit 1-4-5-6-3; but the resistance R being included in the circuit there will be no sudden increase of current in the 5 armature. A moment later when the armature attains normal speed the switch-arm engages the contact c^6 , short-circuiting the resistance.

The field F of the motor is included in a 10 conductor 7, extending from conductor 1 between the line and motor to the contact d' of the field resistance d . The controlling-lever d^2 of the field resistance is connected by a conductor 8 with a segment b^3 , adapted 15 to be engaged by an insulated plate b^4 upon the under side of the armature-starting arm b' in all positions of the starting-arm b' except its normal or dead position. The insulated plate b^4 is arranged to connect the 20 segment b^3 with a segment b^5 , connected by conductor 9 with main-line conductor 3, so that when the starting-arm is advanced and bridges said segments while the controlling-lever d^2 of the field resistance is on segment 25 d' the field F is at full strength in circuit 1-7-8-9-3. During the travel of the arm b' over its resistance-contacts the plate b^4 engages a segment b^6 , which is connected by conductor 10 with conductor 7, including 30 the field. A shunt is thus established about the portion of the field-circuit previously traced, including the field-resistance-controlling arm and its contacts, so that no field resistance could be cut in until the armature 35 resistance shall have been cut out.

As the starting-arm reaches segment b^2 the plate b^4 leaves segment b^6 and engages successively contacts $b^7 b^8$, which control 40 shunts 11 12 about successive portions $d^3 d^4$ of the field resistance, so that no matter where the field-resistance controller is set upon the operation of the starting-arm the shunts will be successively opened and the predetermined field resistance gradually brought into 45 the field-circuit.

The field-resistance-controlling arm d^2 controls the operation of the switch-arm c^3 . The shaft d^3 of the field resistance to which is attached the lever d^2 carries a segmental gear 50 e , adapted to mesh with a segmental gear f , secured to the switch-arm. The gear f is provided with two concave portions $f' f^2$. In the normal positions of the apparatus, with the controlling-arm d^2 on contact d' and the 55 switch-arm c^3 connecting contacts $c' c^2$, the gears occupy the position shown in Fig. 1, with the teeth on gear e on the right side thereof and resting against the concave portion f' of gear f at the right thereof and the 60 teeth of gear f being on the left side thereof. Now assuming the motor is to be brought to its highest speed the starting-arm is thrown clear over until the armature resistance is all cut out and the plate b^4 engages the dead 65 contact b^9 , still connecting, however, seg-

ments $b^3 b^5$. The field-resistance arm d^2 is then moved over its contacts, the gear e riding in the concave portion f' of gear f without operating it. When the arm d^2 reaches the last contact, all the field resistance is cut 70 into the field-circuit, the armature still running on low-voltage current. The gear e occupies the position shown in Fig. 2. As the arm d^2 leaves the last contact and engages contact d' the teeth on gears $e f$ mesh 75 and the arm is swung into engagement with contacts $c^4 c^5$, whereupon the armature is connected with the high-voltage circuit, but with the resistance R in circuit, so that no sudden rush of current passes through the 80 armature. The contact d' is made of some length, and when the arm d^2 is about to leave it the arm c^3 is moved still farther to the left, engaging contact c^6 and shunting the resistance R , thus connecting the armature directly 85 with the high-voltage mains. The gears now occupy the position shown in Fig. 3 with the smooth peripheral surface of gear e resting in the concave portion f^2 of gear f . The arm d^2 may now be moved until it 90 reaches the last contact, whereupon the maximum motor speed is attained with weakened field and armature on high-voltage mains. The gears are now in the position shown in Fig. 4, locked against further 95 clockwise movement. To return the parts to normal position, it is simply necessary to move the lever d' in a contra-clockwise direction twice around its contacts and reverse the starting-arm.

100

I claim—

1. In a multiple-voltage system of speed control for electric motors, the combination with a motor and its circuit, of an armature-resistance for the motor, a controller for said resistance, a field resistance having a controller independent of the starting-resistance controller, the interpolation of the amount of field resistance determined by the field-resistance controller being governed by the 110 starting-resistance controller, a plurality of sources of current of varying voltage, and means operated during the manipulation of said field resistance, for connecting said motor-armature with each of said sources of current. 115

2. In a multiple-voltage system of speed control for electric motors, the combination with a motor and its circuit, of an armature-starting resistance for the motor, a controlling-arm therefor, a field resistance and controlling-arm therefor, adapted to be moved independently of the starting-resistance arm, to determine the maximum field resistance to be inserted in the motor-field, the interpolation of said maximum field resistance being controlled by said starting-resistance arm, sources of current of high and low voltage, and mechanism operated by said field-resistance-controlling arm in its movement for 120 125 130

shifting the connection of the motor from one source of current to another to affect the speed of said motor.

3. In a system of speed control for electric motors, the combination with a motor and its circuit, of a field resistance having a controlling-arm secured to the shaft thereof, a switch-arm, two sources of current, of high and low voltage respectively, terminating upon opposing sets of contacts of said arm, and segmental gearing connecting said shaft and switch-arm, adapted in the operation of said controlling-arm, to shift said switch-arm from one set of contacts to the other, to affect the motor speed.

4. In a multiple-voltage system of speed control for electric motors, the combination with a motor and its circuit, of an armature-starting resistance, and its controlling-arm, the interpolation into the motor-field circuit of the field resistance by its controlling-arm, being controlled by said starting-arm, a switch-arm, two sources of current, of high and low voltage respectively, terminating upon opposing sets of contacts of said switch-arm, and mechanism, controlled by said field-resistance arm in its movement, for shifting said arm from one set of contacts to the other, to vary the motor speed.

5. In a system of speed control for electric motors, the combination with a motor and its circuit, of an armature-starting resistance and its controlling-arm, a field resistance, a controlling-arm for said resistance mounted upon a shaft and adapted to sweep over the contacts of said resistance, the interpolation into the motor-field circuit of said field resistance by its controlling-arm being controlled by said starting-arm, a switch-arm, two sources of current of high and low voltage respectively, terminating upon opposing contacts of said arm, and segmental gearing connecting said shaft and switch-arm, said gearing, when the field-resistance-controlling arm reaches a predetermined contact, being adapted to shift said arm from one set of contacts to the other, thereby varying the motor speed.

6. In a multiple-voltage system of speed control for electric motors, the combination with a motor and its circuit, of an armature-starting resistance and its controlling-arm, a field resistance having a controlling-arm secured to the shaft thereof, said field-resistance-controlling arm being independent of the starting-arm and adapted to be set to determine the maximum field resistance to be inserted in the motor-field, contacts adapted to be engaged by said starting-arm after the armature resistance is cut out thereby, shunts about different portions of the field resistance terminating upon said contacts, whereby the predetermined maximum field resistance may be gradually brought into the field-circuit, a switch-arm, sources of current of high and low voltage, a pair of contacts on each side of said arm, one source of current terminating upon each pair of contacts, and segmental gearing connecting the shaft of the field resistance with said switch-arm, adapted at a predetermined point in the operation of said field-resistance-controlling arm, to shift said switch-arm from one set of contacts to the other, to vary the motor speed.

7. In a multiple-voltage system of speed control for electric motors, the combination with a motor and its circuit, of an armature resistance, a controlling-arm therefor, sources of current of high and low voltage, mechanism for connecting said armature alternately with said sources of current, a field resistance and a controller therefor, adapted to be set independently of said controlling-arm, to determine the amount of field resistance to be inserted in the field-circuit, and means controlled by said armature-starting arm, for bringing said predetermined resistance into the field-circuit.

In witness whereof I hereunto subscribe my name this 11th day of January, A. D. 1906.
